UNITED STATES PATENT OFFICE.

WILLIAM E. SPARKS, OF NEW BRITAIN, CONNECTICUT, ASSIGNOR TO THE KEMPSHALL MANUFACTURING COMPANY, OF SAME PLACE.

DESIGN FOR A SASH-FASTENER FRAME.

SPECIFICATION forming part of Design No. 15,755, dated January 27, 1885.

Application filed October 15, 1883. Term of patent 14 years.

To all whom it may concern:

Be it known that I, WILLIAM E. SPARKS, a citizen of the United States, residing at New Britain, in the county of Hartford and State 5 of Connecticut, have invented and produced a new and original Design for a Sash-Fastener Frame, of which the following is a specification, reference being had to the accompanying drawings, forming part thereof.

10 Figure 1 is a plan view of my newly-designed sash-fastener frame, and Fig. 2 is a side elevation of the same.

Heretofore sash-fastener frames have been made with the base plate slightly flaring and 15 with fluted side edges, which showed plainly only when viewed from one side, and even then the ornamentation has been of a rude character, consisting of mere grooves and ridges or a fluted surface, with nothing like 20 what may be termed "distinctive" ornamental figures or characters.

The essential feature of my design consists of making the contour of the base-plate or the base-plate and keeper at their side edges of a 25 decided tapering form—as, for instance, conical or pyramidal—and providing said tapering edges with distinctive ornamental figures or characters.

A designates the base-plate, which in the 30 main is of a conical form, or, rather, in the form of the frustum of a cone. The tapering or slanting side edges of this base-plate are ornamented by distinctive ornaments a, the same being preferably on a paneled surface,

as shown. The taper of these side edges is 35 such that the ornamental figures a can be distinctly seen when viewed in plan view, as shown by Fig. 1. I also propose to embody this same design in the keeper B, whose tapering side edges are provided with any suitable ornaments, b b. These parts A and B are placed adjacent to each other in use, as shown in the drawings, and when the same design is embodied in both it produces a pleasing harmony. The parts above the base-plate A constitute no part of the design. By making the sides of these parts A and B so tapering that the figures can be seen clearly in plan view 45 also enables them to be plainly seen when viewed from any direction from a plan view 50 to a side view, thereby producing a very pleasing effect.

I claim—

1. The design for a sash-fastener frame herein shown and described, the same consisting of the base-plate or base-plate and keeper having tapering side edges provided with ornamental figures clearly visible in plan view. 55

2. The design for a sash-fastener frame herein shown and described, the same consisting of the keeper having tapering side edges provided with ornamental figures clearly visible in plan view. 60

WILLIAM E. SPARKS.
